DISPENSING MACHINE

Theodor Jungmayr, Stuttgart, Germany, assignor to Firma Fr. Hesser, Maschinenfabrik-Aktiengesellschaft, Stuttgart-Bad Cannstatt, Germany, a corporation of Germany

Filed Mar. 3, 1959, Ser. No. 796,830

Claims priority, application Germany Mar. 17, 1958

7 Claims. (Cl. 222—162)

This invention relates to a dispensing machine for measuring out commodities in powder form and charging containers with them.

It is known to measure out flowable loose material by means of so-called plate dispensing machines having continuously rotating dispensing chambers, and to charge the material thereby into packages. These machines have high rates of output, but are unsuited to the dispensing of some commodities which are inclined to stick and cake together, because such materials do not completely fill the measuring chambers or are not completely evacuated from them.

To cater for materials of this sort, dispensing has been carried out by means of feed screws, the amount of rotation of which per measuring operation can be adjusted to suit the required quantity of filling material. To obtain an increased output in cases of this sort, it has been proposed to arrange a plurality of such screw dispensers side by side in stationary fashion in a single machine and to operate and control them in unison.

This arrangement has the drawback that a plurality of packaging containers, corresponding in number to the screws, must be introduced simultaneously to the filling stations during the dispensing operation and must also be conducted away therefrom simultaneously, and this involves difficulties, particularly in the case of packaging machines with continuously-rotating conveyor means.

The object of the present invention is to avoid this drawback, and to present a high capacity dispensing machine having a plurality of dispensing screws and to which the containers to be filled can be forwarded individually in a continuous series.

For this purpose, in the present invention the dispensing screws are arranged at regular intervals on a rotating distributor plate, and the operation and control of the screws rotating with the plate are derived from the rotary movement of the latter.

This novel screw dispensing machine can give very high rates of output if use is made of an appropriately large number of dispensing screws, and can be built without difficulty into any packaging machine having a continuously-rotating conveyor means.

Three embodiments of the invention are illustrated in the accompanying drawings, in which:

Figure 1 is a cross section through a first embodiment of the screw dispensing machine,

Figure 2 is a plan view of the embodiment illustrated in Figure 1,

Figure 3 illustrates a second embodiment of the invention in which clutches are utilised,

Figure 4 is a plan view of the embodiment shown in Figure 3,

Figure 5 is a partial side view of busbars used in the embodiment of Figures 3 and 4,

Figure 6 is a cross-section through an electromagnetic clutch,

Figure 7 is a cross-section through a mechanical clutch,

2

Figure 8 is a plan view of a third embodiment using cam control means,

Figure 9 is a partial cross-section on an enlarged scale of the embodiment illustrated in Figure 8,

Figure 10 is a plan view of a unidirectional gearing, partially in cross-section,

Figure 11 is a side view of an adjusting instrument.

Referring to Figures 1 and 2, the screw dispensing machine is arranged co-axially in relation to a reversing drum 4 of a continuously rotating conveyor device, for example an endless conveyor chain, a conveyor belt 1, or the like, which conducts the packages P between leading rails 41, 42, 43 continuously to the dispensing machine. Such conveyor devices are well-known to men skilled in the art.

In more detail, the screw dispensing machine comprises a distributor plate 2 which is connected by means of a tube 60 to and rotates with the reversing drum 4, a feed sleeve 9 fixed to the machine frame 44, and a plurality of dispensing screws 8 (for example eight) which are arranged regularly in a circle on the distributor plate 2, and each of which turns in a package-filling sleeve 7. A cone 15 fixed to the plate 2 and a star 10 fixed to the frame 44 uniformly distribute the loose material, conducted through the sleeve 9, to the hopper-form inlets 6 of the filling sleeves 7. The level of the filling material on the distributor plate 2 can be regulated by a sleeve 11 which is displaceable on the feed sleeve 9.

The dispensing and charging out of the filling material into the packages P occurs during the period in which the individual dispensing screws 8 are located above the respective packages P on the reversing drum 4 of the conveyor mechanism, and the screw 8 concerned being operated at this time.

In the embodiment illustrated in Figures 1 and 2, this is implemented by direct engagement between toothed pinions 12 secured to the shafts 13 of the dispensing screws 8 and a circular toothed segment 14 stationary on the machine. The number of rotations of the dispensing screws 8 required to measure out the specific quantity of filling is set by adjustment of the effective length of the toothed segment 14, and for this purpose the segment is made in two parts and overlapping these parts, 14', 14'', to a greater or lesser extent. For this purpose, the part 14'' is provided with a longitudinal slot 46, so that the part 14'' may be secured on the part 14' by means of screws 45 serving also to secure the part 14' to the machine frame.

The shafts 13 of the dispensing screws 8 are rotatably mounted in bearings 47 which are secured to the dispensing plate 2.

In order to prevent filling material falling from the filling sleeves 7 if such sleeves are on the side opposite to the filling side of the machine, there is provided a rail 62. Moreover, there is provided a channel 63 for receiving all parts of filling material falling alongside of the packings P. The drive of the machine comprises an electro-motor 65 which drives by means of a belt 66 a gearing 67, 68. The shaft of wheel 68 drives by means of the gearing 70, 71 the shaft 72 of the drum 4 of the conveyor 1.

In the embodiment illustrated in Figures 3-7 the dispensing screws 8 are driven by a fixed toothed ring 18 which is in permanent mesh with a pinion 17 loose on each of the respective screw shafts 13. The screw shaft 13 concerned is disengageably coupled to its pinion 17 through a suitable clutch. In the example illustrated in Figures 3-6, use is made of electro-magnetic clutches 16 which can be energised at intervals, selected as required, through circular arcuate and two-part busbars 22 and 23 of adjustable length. The busbar 22 is embedded in an insulating body arranged on the machine frame 44,

The length of the upper busbar may be changed by means of its parts 23' and 23" in the same way as described for the toothed segment 14 in Figures 1 and 2.

Current pick-ups 20, 21 are provided on each clutch 16. These pick-ups are secured to the bearings 42 of the shafts 13 and in contact with coils 26, 27 which transfer the electric current to the rings 28, 29 of the electromagnetic clutches 16. The clutches 16 of the individual dispensing screws 8 thus remain effective as long as the pick-ups 20, 21 of the clutches 16 get and are successively in sliding contact with the busbars 22, 23. The period of energisation, and thus the number of rotations of the screws, per dispensing operation can be adjusted as desired by lengthening or shortening the said bars 22, 23.

Instead of electrically-operated clutches 16, use may be made of merely mechanical clutches 50, operated and controlled through a fixed, adjustable guide rail 51 (cf. for example in Fig. 7). The principle on which the dispensing screws 8 are driven is not thereby changed.

The individual clutches 50 are arranged within casings 52 which serve simultaneously as bearings for the screw shafts 13. A toothed pinion 17 engaging with the toothed ring 18 (Fig. 4) is secured to the part 53 and loosely mounted on the screw shaft 13. The upper part 54 is axially shiftable on shaft 13, but rotates therewith because of the spline 55. A lever 57 has a forked end which engages the annular notch 56 of the upper part 54, by means of which the guide rail 51 controls clutch 50. If the lever 52 is free from the guide rail 51, the clutch 50 becomes operative by means of the pressure of spring 58.

In the embodiment illustrated in Figures 8-11, the dispensing screws 8 are operated by a fixed cam rail 30 acting on each of the screw shafts 13 through an associated toothed gearing. When the distributor plate 2 rotates, rollers 32 arranged on toothed discs 31 bear against the cam rail 30 and the discs 31 are thereby turned, during the course of the rotational movement of the plate 2, about their pivots. The toothed discs 31 each have inner teeth 34 which mesh with a pinion 35. Each pinion 35 is firmly connected to a pinion 36 and is rotatably mounted in the distributor cover 2'. A further pinion 37 engages pinion 36, and is coupled to the corresponding screw shaft 13 through a free wheel device 38 of well known type, for example a unidirectional free wheel.

A second cam rail 39, which is rockable about a pivot 40, but is adapted to be fixed on the machine is used to pivot the toothed discs 31 back into their initial angular dispositions in the opposite direction of rotation after the dispensing movement has been transmitted therefrom. The free wheel device 38 incorporated therein allows this back rotation without affecting the screw 8.

Each free wheel device 38 comprises a bell-like part 70, Fig. 10, which is secured to the pinion 37, and a saw-like formed part 71 engaging with the bell 70 and secured to the screw shaft 13. There are arranged, between the individual teeth of the part 71 and the bell 70, rollers 72 which are urged by springs 73 against the bell 70. If the bell 70 is turned in the direction of the pressure exerted by the springs 73, the rollers 72 will be clamped between the bell 70 and the part 71 and transfer the rotation to the part 71. In the opposite direction of rotation, the bell 70 will urge the rollers 72 against the teeth, whereby the clamping action is interrupted so that no transfer of the rotation takes place.

To enable a specific quantity of dispensed material to be pre-set, the cam rail 39 is turned about its pivot 40, and as a result the position for the start of a fresh dispensing operation by each toothed disc 31 is modified. Thus the cam rail 39 enables the angle of pivoting of the toothed discs 31 to be set to any required value, and

thus the number of rotations of the corresponding screw per dispensing operation to be adjusted in the same way.

The cam rail 39 may be adjusted by means of a spindle 75 and a hand wheel 82, the spindle being turnably mounted in bearings 76, 77 on the machine frame 44 (cf. Fig. 11). A nut which is screwed on the spindle 75, is prevented from turning. The nut 78 has a bolt 80 which engages with a longitudinal slot 81 of the cam rail 39. This mechanism allows also to adjust the quantity of dispensed material while the machine is running.

To comply with the need for slow run of the dispensing screws 8 at the beginning of their rotation, which is important to secure an exact dispensing operation, the starting portion of the cam rail 30 is given a shallow curvature or is to some extent eccentric, whereby there is only a relatively slight pivoting of the toothed discs 31 at this early part per degree of rotary movement of the distributor plate 2.

The invention is not limited to the embodiments which have been illustrated and described above, but can be carried out in various other ways.

What I claim is:

1. A machine of the type specified comprising, in combination, a rotatable distributor plate, means to feed flowable loose material upon said plate, means adapted to rotate said plate continuously, a plurality of dispensing screws each adapted to rotate in a package filling sleeve having a hopper-like inlet, the said hopper-like inlets being arranged in a circle at the underside of the said distributor plate, means adapted to drive and control the rotation of the said dispensing screws from the rotary motion of the said distributor plate, a fixed cam-like rail arranged above one half of the distributor plate, a partly toothed disc loosely mounted upon the shaft of each dispensing screw, a roller arranged on said disc and bearing against said fixed cam-like rail, a gearing adapted to transmit rotation from the said disc to a pinion loosely mounted on the shaft of the dispensing screw, and a unidirectional gearing arranged between said pinion and the shaft of the dispensing screw.

2. In a machine as specified in claim 1, a fixed toothed segment arranged above said distributor plate, and means adapted to rotate the said dispensing screws comprising a pinion fixed to the shaft of each dispensing screw and arranged to engage, during the rotation of the distributor plate, temporarily the said toothed segment.

3. In a machine as specified in claim 2, means adapted to adjust the arcuate length of the said toothed segment.

4. Machine as specified in claim 1, in which the starting portion of the said cam-like rail has a shallow curvature.

5. Machine as specified in claim 1, in which a second cam-like rail is arranged above the other half of the distributor plate and adapted to pivot the said partly toothed discs back into their initial angular dispositions in the opposite direction of rotation.

6. Machine as specified in claim 5, in which the said second cam-like rail is rockably and fixably mounted.

7. In a machine as specified in claim 1, a fixed toothed ring arranged above the said distributor plate, a pinion mounted loosely on the shaft of each dispensing screw and permanently in mesh with said toothed ring, each pinion being disengageably coupled to its shaft, and means adapted to couple each pinion with its shaft for a predetermined period.
